P. W. NELSON, INVENTOR.

UNITED STATES PATENT OFFICE.

PETER W. NELSON, OF MOLINE, ILLINOIS.

AUTOMATIC REIN-HOLDER.

SPECIFICATION forming part of Letters Patent No. 233,110, dated October 12, 1880.

Application filed August 7, 1880. (No model.)

To all whom it may concern:

Be it known that I, PETER W. NELSON, a citizen of the United States, residing at Moline, in the county of Rock Island and State 5 of Illinois, have invented certain new and useful Improvements in Automatic Rein-Holders; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention is intended to be applied to the sides of wagon-boxes and other vehicles of every description, and has for its object a more ready and convenient mode of enabling teamsters and others to dispose of the reins of their 20 horses when desiring to stop wagons, &c.; and it consists in the construction and novel arrangement of the various parts thereof, which will be hereinafter more fully explained.

In the accompanying drawings, Figure 1 is 25 a front elevation, partly broken away. Fig. 2 is a vertical section on line $y-y$, Fig. 1, and Fig. 3 is a transverse section on line xx , Fig. 1.

A and A' represent two parallel jaws having teeth a a' formed on their upper ends, one 30 of which, A, is movable and made slightly convex, and the other jaw, A', is made concave and is stationary, both being pivoted together in such a manner that they fit snugly against each other when allowed to spring together 35 for the purpose of more firmly retaining the reins in their grasp and preventing them from slipping. This jaw A' has also two curved or peculiarly-constructed side pieces or plates, B B, between which the jaw A articulates or

moves by means of a pivot, b, which connects 40 the jaws together.

C is a spiral spring, which rests upon lugs D D, formed upon the inside of the jaws A and A', one end of the spring C, which surrounds and rests upon the lug D in the movable jaw 45 A, fitting in a circular recess, d, in the same, the other end resting on the lug D upon the stationary jaw A' on the inside thereof. The lower end of jaw A serves as a handle, E, for opening and closing the jaws when desired. 50

Operation: It will thus be obvious that when the teamster or driver desires to stop his team from time to time, as occasion may require, all that will be necessary for him to do is to press upon the lower portion or handle, E, of the 55 movable jaw A and open the same, and then slip his reins in between said jaws, and when he releases his hand the pressure of the spring, acting upon the aforesaid jaws, closes them 60 upon the reins and holds them tightly in their grasp, and when he wants to release the reins the same operation is repeated.

Having thus described my invention, what I claim as new, and desire to secure by Letters Patent, is—

The concave and convex serrated or toothed jaws A and A', the latter provided with the side plates, B B, and spring C, lugs D D, and circular recess d, constructed, combined, and arranged as herein described, and for the purpose set forth.

In testimony whereof I affix my signature in presence of two witnesses.

PETER WINDQUEST NELSON.
